JOHN H. SPANGLER, OF MINNEAPOLIS, MINNESOTA, ASSIGNOR, BY DIRECT AND MESNE ASSIGNMENTS, OF ONE-FOURTH TO ADAM M. SMITH AND ONE-FOURTH TO JOHN A. NELSON, BOTH OF MINNEAPOLIS, MINNESOTA.

EGG-SHIPPING CASE.

1,117,529.

Specification of Letters Patent. Patented Nov. 17, 1914.

Application filed January 15, 1914. Serial No. 812,213.

To all whom it may concern:

Be it known that I, JOHN H. SPANGLER, a citizen of the United States, residing at Minneapolis, in the county of Hennepin and 5 State of Minnesota, have invented certain new and useful Improvements in Egg-Shipping Cases; and I do hereby declare the following to be a full, clear, and exact description of the invention, such as will enable others skilled in the art to which it 10 pertains to make and use the same.

My invention has for its object to provide an efficient shipping case or carton, especially adapted for use in shipping eggs by 15 parcel post, and which, while very light and of very small cost, will have the required strength and will so hold the eggs in suspension therein that they will not be broken even by the roughest usage encountered in 20 shipping.

To such ends, generally stated, the invention consists of the novel construction and arrangement of parts hereinafter described and defined in the claims.

25 In the accompanying drawings which illustrate the invention, like characters indicate like parts throughout the several views.

Referring to the drawings: Figure 1 is a 30 plan view with some parts broken away, showing the improved shipping case; Fig. 2 is a vertical section taken on the line $x^2 x^2$ on Fig. 1; Fig. 3 is a transverse section taken on the line $x^3 x^3$ on Fig. 1; Fig. 35 4 is a view in end elevation showing the filler or inside elements of the case, some of the said parts being separated from each other to illustrate the manner of assembling the same; Fig. 5 is a view in elevation; and 40 Figs. 6 and 7 are perspective views showing the different kinds of elements used to make up the filler or inside structure of the case.

Referring first to Figs. 5, 6 and 7, the 45 numerals 1, 2 and 3, respectively, indicate the elements which make up the said filler or inside structure of the case. The case may be designed to hold any desired number of eggs, but as shown, it is designed to hold one dozen eggs, and the inside structure or 50 filler thereof, is made up of five of the elements 1, three of the elements 2, and three of the elements 3. As preferably constructed, the elements 1, which are called partition plates, are of disk-like form, while the ele-

ments 2 designated as trough forming plates, 55 are bent into channel shape form in cross section, and the elements 3, which are designated as cover plates, are in the form of elongated flat strips. The elements forming the case may be made of any suitable 60 material, but all thereof, are preferably constructed from heavy and stiff cardboard. The disk-like partition plates 1 are formed with slits 4 that are arranged in parallel pairs that extend nearly but not quite 65 radially inward, and they are also formed with one-half as many slits 5 that intersect one of each pair of slits 4 approximately at a right angle. The trough plates 2 are formed with transverse slits 6 that extend 70 across their bottoms and about one-half way up their sides, and in number are equal to the number of partition plates 1 employed. The cover plates 3 are formed with slits 7 75 extended from one edge, transversely about one-half way across the same, and which, in number, are equal to the number of plates 1.

The manner of assembling the filler or inner structure of the case is as follows: 80 First, the trough plates 2, while properly bent into channel shape form, approximately as shown in Fig. 7, are slipped onto the several plates 1 in such manner that their slits 6 embrace the portions between 85 parallel slits 4 of such partition plates, and in such manner that the outer unslit portions are embraced by the said slits 4. This interlocks the trough plates 2 to the partition plates in such manner that the said trough 90 plates are held in proper form and the said trough plates properly space the partition plates. Otherwise stated, the said partition plates and trough plates, when thus assembled, mutually brace each other. The 95 eggs may then be placed in the several partitions of the several troughs and the troughs may then be closed by sliding the cover plates 3 into the slits 4 in such manner that the slits 7 of the said plates 3 embrace the undercut parts of those portions of the partition plates 1 which are between the pairs of slits 4. The cover plates, when thus applied, not only close the egg holding troughs but afford additional braces for 100 spacing the partition plates and for further reinforcing the filler of the case. When the 105 said parts 1, 2 and 3 are assembled and in-

terlocked, as above described, they afford a complete egg case or holder, but for the purpose of shipment of eggs by parcel post, would be too liable to be broken, and hence, 5 not a satisfactory shipping case. Hence, I employ in connection therewith, an outside casing which may be cheaply made from a heavy and stiff sheet of cardboard 8 bent into cylindrical form and having radially 10 inturned abutting edges 9 that are forced into radial slits 10 formed in the partition plates 1. When the outside casing is thus applied, it will be securely held to the partition plates and will not only reinforce, 15 protect and strengthen the filler, but will afford an outer wall space outward from the egg holding troughs, and from which the egg holding troughs are so spaced that the eggs will be held in sort of suspended cradles where they will not be subject to any 20 direct or substantially direct blows or jars. Preferably, caps 11 are slipped onto the ends of the cylindrical casing 8, and these serve to securely hold the outer casing 8 in- 25 terlocked to the partition plates 1. The caps 11, it will be noted, are spaced from the outer partition plates 1 so that the latter will not be subject to direct blows received at the ends of the case. To make the inter- 30 mediate portions of the compartments of the trough plates 2 expansible so that they will closely fit eggs of different sizes, they are shown as provided with slots 12 at their angles. 35 In actual practice, this egg case has been found efficient, in all respects, as an egg carrying case or carton, for shipment by parcel post. It has also been found that it can be made in large quantities at an extremely small 40 cost, in fact, at a cost considerably less than the cost of returning the same to the sender by parcel post. An egg shipping case of this character may, therefore, be economically used for shipping purposes, even where it is 45 used for only one shipment. It may, however, be used over and over again a good many times. As already indicated, it may be made in different sizes for carrying a greater or less number of eggs. In fact, I 50 have found that by increasing its diameter very slightly, its egg carrying capacity may be increased to carry two dozen or more eggs.

The case is primarily designed as an egg 55 shipping case, but of course, it may be used for shipping other fragile articles.

What I claim is:

1. A shipping case of the kind described comprising partition plates and trough 60 forming plates interconnected, with the said trough forming plates extended outward in different directions and spaced around the centers of said partition plates to form a plurality of circumferentially spaced egg 65 receiving troughs divided into compart-

ments by said partition plates, and means closing the outer sides of the said troughs.

2. A shipping case of the kind described comprising partition plates and trough forming plates interconnected, with the said 70 trough forming plates extended outward in different directions and spaced around the centers of said partition plates to form a plurality of circumferentially spaced egg receiving troughs divided into compartments 75 by said partition plates, cover plates interlocked to said partition plates and closing the outer sides of the said troughs, the said parts constituting a filler, and an outer casing inclosing said filler.

3. A shipping case of the kind described, comprising a plurality of disk-like partition plates having inwardly extended pairs of trough plate receiving slits, trough forming plates having slits for receiving portions of 80 said partition plates, said parts when assembled, being interengaged and affording a plurality of compartments, plates closing 85 the troughs, the said parts constituting a filler, and an outer casing surrounding said 90 filler and spaced from the trough forming plate thereof by the said partition plates.

4. A shipping case of the kind described, comprising a plurality of disk-like partition plates having inwardly extended pairs of 95 trough plate receiving slits, trough forming plates having slits for receiving portions of said partition plates, said parts when assembled, being interengaged and affording a plurality of compartments, plates closing 100 the troughs and the said parts constituting a filler, and an outer casing surrounding said 105 filler and spaced from the trough forming plate thereof, by the said partition plates, said outer casing being formed from a sheet having inturned abutting edges seated in slits formed in the said partition plates.

5. A shipping case of the kind described, comprising a plurality of disk-like partition plates having inwardly extended pairs of 110 trough plate receiving slits, trough forming plates having slits for receiving portions of said partition plates, said parts when assembled, being interengaged and affording a plurality of compartments, plates closing 115 said troughs, and the said parts constituting a filler, an outer casing surrounding said filler and spaced from the trough forming plate thereof, by the said partition plates, said outer casing being formed from a sheet 120 having inturned abutting edges seated in slits formed in the said partition plates, and caps telescoped over the ends of said outer casing.

6. An egg case comprising disk-like partition plates, channel-shape trough forming plates and flat cover plates, said partition plates having pairs of inwardly extended parallel trough forming plate receiving slits 125 and cover plate receiving slits intersecting 130

certain of said trough plate receiving slits, said trough plates having slits extending across their bottoms and part way up their sides, to adapt them to straddle portions of 5 said partition plates, and the said cover plates being engageable with the cover plate receiving slits of said partition plates and having slits at one edge to straddle portions of said partition plates.

- 10 7. An egg case comprising disk-like partition plates, channel-shape trough forming plates and flat cover plates, said partition plates having pairs of inwardly extended parallel trough plate receiving slits and 15 cover plate receiving slits intersecting certain of said trough plate receiving slits, said trough plates having slits extending across their bottoms and part way up their sides, to adapt them to straddle portions of 20 said partition plates, and the said cover plates being engageable with the cover plate receiving slits of said partition plates and having slits at one edge to straddle portions of said partition plates, in combination with an 25 outer casing formed from a plate bent into cylindrical form and having inturned abutting edges interlocked with slits in the said partition plates.

8. An egg case comprising disk-like partition plates, channel-shape trough forming 30

plates and flat cover plates, said partition plates having pairs of inwardly extended parallel trough forming plate receiving slits and cover plate receiving slits intersecting certain of said trough plate receiving slits, 35 said trough plates having slits extending across their bottoms and part way up their sides, to adapt them to straddle portions of said partition plates, the said cover plates being engageable with the cover plate receiving slits of said partition plates and having slits at one edge to straddle portions of 40 said partition plates, in combination with an outer casing formed from a plate bent into cylindrical form and having inturned 45 abutting edges interlocked with slits in the said partition plates, and caps telescoped onto the ends of said outer casing, the said outer casing being spaced from the trough forming plates by said partition plates and 50 the said caps being spaced from the outer end partition plates by projecting ends of said trough forming plates.

In testimony whereof I affix my signature in presence of two witnesses.

JOHN H. SPANGLER.
